Primary Examiner — Kelley A Donnelly*(74) Attorney, Agent, or Firm* — Morris O'Bryant
Compagni Cannon, PLLC(57) **CLAIM**

The ornamental design for the adjustable shelf, as shown and described.

DESCRIPTION

FIG. 1 is a perspective view of the present invention; FIG. 2 is a front side view of the present invention; FIG. 3 is a back side view of the present invention; FIG. 4 is a left side view of the present invention; FIG. 5 is a right side view of the present invention; FIG. 6 is a top side view of the present invention; and, FIG. 7 is a bottom side view of the present invention. The broken lines in the drawings depict portions of the adjustable shelf that form no part of the claimed design.
